ABSTRACT: A transistor with interdigitated emitter and base fingers, in which the emitter has a web portion for feeding current to the fingers, and metal layers on both the web and the fingers. The emitter finger metal layers are spaced from the web portion metal layers to introduce a ballasting resistance, with that portion of each finger metal layer proximate to the web portion being substantially wider than the remainder of the finger layer, and interspersed between the corresponding base finger and the emitter web portion to maintain a uniform distance between the base finger and the emitter finger metal layer.

POWER TRANSISTOR

BACKGROUND OF THE INVENTION

The present invention relates to transistors required to handle relatively large amounts of power. High power transistors usually include an emitter region having a relatively large area so that the power is distributed over the device to keep the power per unit area within safe limits. It has previously been found that, in a power transistor having a relatively large area emitter, emitter-base injection occurs mainly around the periphery of the emitter. It has therefore become the practice to define the emitter region so that it has as large a periphery as possible in relation to area.

A number of different configurations have been adopted to secure relatively large emitter periphery. One of these is a star, or similar shape, which include a plurality of convolutions extending radially outwardly from a hub portion. Another is a multiplicity of separate emitter sites connected in parallel to function as a single emitter. Still another configuration is one in which the base region and the emitter region are of generally comb shape with a web portion and interdigitated fingers. The emitter may be a double comb with the web portions back to back.

The use of such configurations as described above has greatly improved current handling capability. Nevertheless, it has been found that, because of various triggering mechanisms, at present difficult to avoid, second breakdown occurs across the emitter-base junction because current is focused in one or more small spots. The focusing of current in small spots has previously been decreased by inserting ballasting resistors in series with the emitter in order to limit the maximum current that can flow between the emitter and base. In general, this expedient has been highly successful in reducing the difficulty. But it has proved to be more difficult to apply to some emitter configurations than to others.

It has also previously been proposed to utilize emitter ballasting resistors in that type of emitter which has a generally comb shape with fingers extending out from a central web portion which serves as a current feed path. This has been accomplished by leaving a space between the metal layer which covers the web portion of the emitter and the metal layer covering each finger portion, since this forces current traveling to the fingers to travel a given distance through the more highly resistive semiconductor. However, spacing the finger contact metal from the web portion contact metal does not alone improve the second breakdown characteristics, because in prior art devices, that portion of the emitter base junction nearest the extremities of the base fingers had been formed too close to the emitter web portion. Thus, the IR drop between this extremity and the emitter web was less than the IR drop in the spacing between the emitter web contact layer and the emitter finger metal, which, in essence, obviated the benefits derived from the ballast resistance spacing.

In solving the above problem, it was determined that if the length of the base finger was controlled in relationship to the ballasting resistance spacing, the two IR drops may be made equal, and the benefits of the ballasting spacing may be realized. However, a reduction in base finger length results in a commensurate reduction in emitter periphery, which is important in determining the current handling characteristics of the device. Thus, it would be desirable to employ the ballasting resistance spacing between the emitter web and finger contact metals, and still maintain an optimum emitter periphery.

SUMMARY OF THE INVENTION

A power transistor of the present invention comprises emitter, base, and collector regions of alternate conductivity types, having a PN junction between the emitter and the base regions, and between the base and collector regions. The emitter region has a central web portion, and fingers extending outwardly from the web portion, with a metal contact layer covering part of the emitter web portion. The base region includes base fingers interdigitated with the emitter fingers.

The emitter region also includes a metal contact layer on each emitter finger, with each contact layer having a proximal portion which is adjacent to, but separated from, the web portion contact layer so as to introduce a ballasting resistance therebetween. The proximal portion of each emitter finger contact layer is substantially wider than the remainder, so that the proximal portion is interspersed between the extremities of the corresponding base finger and the web portion of the emitter region, to maintain a uniform distance between the base finger and the emitter finger contact layer.

THE DRAWING

The single FIGURE of the drawing is a plan view of the top surface of a transistor constructed in accordance with the present invention.

DESCRIPTION OF THE PREFERRED EMBODIMENT

A transistor 10 constructed in accordance with the present invention comprises a collector region (not shown) and a base region 12 adjacent the collector region, with a PN junction therebetween. The base region 12 may either be an epitaxial layer grown on the collector region and of opposite conductivity type to the collector region, or it may be a pocket diffused into the collector region. The transistor 10 also includes an emitter region 14 which may be formed by diffusing impurities into the base region 12 so that the emitter region 14 is of a conductivity type opposite to the base region. The device may either be of NPN or PNP configuration.

Between the base region 12 and the emitter region 14 there is a PN junction 16 defining the boundary between the two regions. The base region, where it surrounds the emitter region, comprises a web portion 18 and a plurality of fingers 20 extending outwardly from the web portion 18 and perpendicular thereto.

The emitter region 14 also includes a web portion 22 and fingers 24 which are interdigitated with the base fingers 20. The emitter web portion 22 is partly covered with a metal contact layer 26 which provides a low resistance feed-through for current entering the emitter region 14. Similarly, each emitter finger 24 is partially covered with a metal contact layer 28, which does not touch the junction 16.

The emitter finger contact layers 28 are separated from the emitter web portion metal layer 26 by a distance "d." Thus, a definite resistance value is introduced in the current path between the web portion metal layer 26 and the finger metal layer 28, the magnitude of which depends upon the distance of separation "d" and the sheet resistance of the emitter region 14.

Further, the emitter finger contact layer 28 is spaced from the PN junction 16 by a distance "s," which introduces a resistance between the layer 28 and the junction. In order to maintain a uniform distance "s" between the junction 16 and each emitter finger contact layer 28, each contact layer has a proximal portion 30 which is substantially wider than the remainder of the contact layer, and is interspersed between the base finger 20 and the emitter web portion 22 to maintain a uniform distance "s" at all points.

The transistor 10 further includes a base region metal layer 32 having a web portion contact layer 34 and base finger contact layers 36.

While the proximal portion 30 of each emitter finger contact layer 28 is shown in the drawing as generally triangular in shape, it will be understood that the proximal portion 30 may have any tapered, rounded, or chamfered shape; the important consideration being that the distance "s" between the emitter finger contact layer 28 and the emitter-base junction 16 is uniform at all points. The actual dimensions of the ballast resistance spacing "d" and the finger metal-to-junction distance "s" is a design criteria; by way of example, the spacing "d" may be 1.0 mil. and the distance "s" may be 2.0 mils.

The transistor 10 may be fabricated by methods well known in the art. The emitter and base contact layers may comprise a malleable metal, such as a tin-lead alloy or aluminum, or a

refractory metal, such as tungsten; however, the tin-lead alloy is preferred.

By utilizing a portion of the emitter finger contact layer between the extremity of the base finger and the emitter web portion, the need for reducing the length of the base finger is avoided. Thus, the dimensions of the emitter periphery may be designed independent of ballast resistance considerations. Further, transistors constructed as described above have improved resistance to second breakdown; the devices can be operated safely at considerably higher voltages than previously known transistors of this same general type.

What we claim is:

1. A transistor comprising:
  - a. a semiconductor having a surface;
  - b. a first conductivity type collector region in the body;
  - c. a second conductivity type base region in the body adjacent the collector region with a base-collector junction therebetween, a portion of the base region extending to the surface;
  - d. an emitter region extending into the base region from the surface, with an emitter-base junction therebetween;
  - e. the emitter region comprising a central web portion and fingers extending outwardly from the web portion;
  - f. a metal web contact layer covering part of the emitter web portion;

15

20

25

g. the base region including base fingers interdigitated with the emitter fingers;

h. a metal contact layer on each emitter finger, each contact layer having a proximal portion adjacent to, but separated from, the emitter web contact finger so as to introduce a ballasting resistance therebetween; and

i. means for providing a substantially uniform resistance between the metal web contact layer and each of the base fingers, the means comprising the proximal portion of each emitter finger contact layer being substantially wider than the remainder of the layer, so that the proximal portion is interspersed between the corresponding base finger and the web portion to maintain a uniform distance between the base finger and the emitter finger contact layer.

2. A transistor in accordance with claim 1, wherein the proximal portion of the emitter finger layer is substantially triangular in shape.

3. A transistor in accordance with claim 1, wherein the uniform distance between the base finger and the emitter finger layer is greater than the ballast resistance spacing between the proximal portion of the finger layer and the web portion metal layer.
